UNITED STATES PATENT OFFICE.

FRITZ BLUMER, OF ENGI, SWITZERLAND.

AUTOMATIC STOP-MOTION MECHANISM FOR POWER-LOOMS.

No. 888,300.

Specification of Letters Patent.

Patented May 19, 1908.

Application filed September 19, 1904. Serial No. 225,133.

To all whom it may concern:

Be it known that I, FRITZ BLUMER, a citizen of the Swiss Confederacy, and resident of Engi, Canton of Glarus, Switzerland, have invented certain new and useful Improvements in Automatic Stop-Motion Mechanism for Power-Looms, of which the following is a specification.

This invention relates to an automatic 10 stop motion mechanism for power looms which, when a thread of the warp breaks, acts directly upon the disconnecting fork of the batten and thus automatically stops the loom.

15 The accompanying drawings represent this invention diagrammatically:—

Figure 1 is a side elevation of this new stop motion mechanism complete. Fig. 2 is a fragmentary view of the hook. Fig. 3 is a 20 plan of the parts shown in Fig. 1. Figs. 4 and 5 are details of the guide. Fig. 6 is an elevation of the feeler. The remaining views are details of the weft stop mechanism.

The warp threads coming from the warp 25 beam pass as shown over a guide bar or rail *c* through eyes of the detector plates *P*, *P'*, slotted and mounted on guide bars *d*, *d'* and grouped by three arms *e*, *e'*, *e''*, all connected and supported by braces *t* much after the 30 manner disclosed in my U. S. Patent 830561 dated Sept. 11, 1906. Lateral movement of the detector plates may also be prevented by stops *K* recessed and applied as in said patent.

A' designates an oscillating feeler moving 35 below said detector plates and their guides and preferably carried by a frame *A* mounted on a rod *V*. A cam *C* fixed on a shaft *J* impinges against a bent rod *B* carried by said frame to impart to the latter a yielding motion in one direction; while a spring *D* secured 40 to a support *D'* moves it in the opposite direction.

Z designates an articulation connecting the frame with a rod *E*, which latter connects 45 with a bell-crank lever *H* pivoted at *x* and having a substantially horizontal arm *h* on which rests an elbow *p* at the lower end of a hook *P* whose upper end engages the tail of the weft fork *S*—all as indicated in Fig. 1. 50 The latter is pivotally supported by a rod *M* suitably connected with the shipper handle *R* in proper position so that when its hooked rear end is depressed it will be engaged and drawn back by the weft hammer *F*, and 55 thereby stop the loom.

In order that the connection between the

hook *P* and fork *S* may be rendered adjustable, I employ mechanism best seen in Figs. 9 and 10, and illustrated in plan view in Fig. 3. The collar *T* is longitudinally adjustable upon the rod *M* by a set screw *U*, and preferably has a depending portion *V* apertured to surround the body of the hook *P* and permit the latter to reciprocate vertically. By loosening the set screw and adjusting said 60 collar along the rod *M*, the point of engagement of the hook *P* upon the tail of the weft fork *S* may be brought nearer to or further from the pivotal support of the latter as will be understood.

70 The operation is as follows: When a warp thread breaks its detector plate drops into the path of the oscillating feeler, which is thereby held in the full line position in Fig. 1; and through the rod *E* and lever *H*, the 75 hook *P* is depressed and the tail of the weft fork *S* dropped to a position to be actuated by the weft hammer *F* to cause the stopping of the loom.

What is claimed as new is:

1. In a stop motion mechanism for looms, the combination with detector plates supported by the warp threads, a weft fork pivotally supported, and the weft hammer adapted to engage said fork; of an oscillating feeler mounted below said plates, an adjustable connection between said feeler and the tail of said fork, a bent rod mounted on the feeler, a cam pressing the rod in one direction, and a spring pressing the feeler in 80 the opposite direction.

2. In a stop motion mechanism for looms, the combination with detector plates supported by the warp threads, a weft fork pivotally supported, and the weft hammer 85 adapted to engage said fork; of an oscillating feeler mounted below said plates, yielding means for moving it in opposite directions, a hook engaging the tail of the fork, connections between the feeler and hook, 90 and a collar adjustable parallel with the length of the fork and having an apertured portion loosely engaging said hook.

3. In a stop motion mechanism for looms, the combination with detector plates supported by the warp threads, a weft fork 100 pivotally supported, and the weft hammer adapted to engage said fork; of an oscillating feeler mounted below said plates, a hook engaging the tail of the fork and having an 105 elbow, a bell-crank lever on one arm of which said elbow rests, connections between

its other arm and said feeler, a rod parallel with the fork, and a collar adjustable longitudinally on said rod and loosely engaging said hook for adjusting its point of connection with said fork.

4. In a stop motion mechanism for looms, the combination with detector plates supported by the warp threads, a weft fork pivotally supported, and the weft hammer
10 adapted to engage said fork; of an oscillating feeler mounted below said plates, a hook engaging the tail of the fork and having an elbow, a support for said elbow, means for raising and lowering said support by the

movements of the feeler, a rod pivotally supporting said fork and standing parallel with its tail, a collar mounted on said rod and having a depending portion apertured and loosely surrounding the hook, and a set screw for adjusting the position of the collar 15 on the rod and hence of the hook on the fork.

In testimony whereof I have hereunto set my hand in presence of two witnesses.

FRITZ BLUMER.
